PNEUMATIC TIRE TREAD AND BUTTRESS

Gerhard Franz-Josef Senger, Aachen, Germany, assignor
to Uniroyal, Inc.

Filed Feb. 24, 1975, Ser. No. 552,081

Claims priority, application Germany Sept. 25, 1974

Term of patent 14 years

Int. Cl. D12—15

U.S. Cl. D12—136

Fig. 1.

FIG. 1 is a perspective view, partly schematic, of a pneumatic tire tread and buttress embodying my new design, it being understood that the pattern is repeated through the circumference of the tread and buttress, as shown schematically by solid lines, and that the buttress pattern is repeated on the opposite side;

FIG. 2 is an enlarged, fragmentary developmental plan view of the tread and buttress of FIG. 1; and

FIG. 3 is an enlarged sectional view of the tread and buttress, taken substantially as indicated by line 3-3 of FIG. 2.

I claim:

The ornamental design for a pneumatic tire tread and buttress, substantially as shown and described.
